COMBUSTION CONTROL

L. V. Andrews, Worcester, Mass., and Charles M. Terry, Decatur, Ill., assignors to A. W. Cash Company, Decatur, Ill., a corporation of Delaware

Application November 10, 1931, Serial No. 574,156

16 Claims. (Cl. 236—26)

This invention relates to combustion control, and more particularly to a method and apparatus for controlling the combustion of pulverized fuel.

In burning pulverized fuel by the direct fired system, it is the practice to reduce the fuel to a desired degree of fineness in a pulverizing apparatus and deliver the finely divided fuel by means of a current of so-called primary air directly from the pulverizer to a furnace. The additional or secondary air required to complete the combustion is usually supplied at the furnace. The rate of combustion is controlled by varying both the supply of secondary air delivered to the furnace and the supply of coarse fuel delivered to the pulverizer. It has already been proposed to control both of these variables automatically in accordance with the demand on the furnace.

These automatic control systems as heretofore arranged have not, however, proven entirely satisfactory. Certain difficulties have been encountered in operation, particularly when the demand for heat is unsteady and subject to rapid fluctuations. It is found that the efficiency of combustion under these conditions is considerably less than that theoretically obtainable, and the ratio of the fuel and air supplied to the furnace is at times too high and at other times too low. This results in a waste of fuel and the occasional production of smoke.

It is accordingly the main object of the present invention to overcome these difficulties and to provide a method and apparatus whereby a pulverized fuel burning system may be controlled to provide efficient combustion at all times, regardless of frequent and rapid changes in the demand for heat.

It is a further object of the invention to provide a method and apparatus which will ensure the delivery of the correct proportions of fuel and air to the furnace at all combustion rates and particularly during periods of change in demand.

It is a further object of the invention to provide a combustion control apparatus which may be easily and simply adjusted to compensate for variations in operating conditions encountered at different furnace installations.

With these and other objects in view, as will be apparent to those skilled in the art, the invention resides in the combination of parts and the steps of the process set forth in the specification and covered by the claims appended hereto.

Referring to the drawings illustrating one embodiment of the invention, and in which like reference numerals indicate like parts,

Fig. 1 is an elevation of an automatically con-

trolled direct fired pulverized fuel burning installation;

Fig. 2 is an enlarged view, partly in section, showing the construction of the master regulator;

Fig. 3 is a view similar to Fig. 2, showing the construction of the secondary regulator;

Fig. 4 is an enlarged cross section of the four-way pilot valve which controls the movements of the master regulator piston; and

Fig. 5 is an enlarged cross section of one of the special valves provided on the secondary regulator.

In the embodiment of the invention illustrated in the drawings, we have shown a steam generating furnace arranged to burn pulverized fuel, comprising a combustion chamber 10 and a boiler 11, the boiler being connected by a pipe 12 to a main steam header 14, which may lead to a steam turbine or other apparatus arranged to use the steam. In order to supply pulverized fuel for combustion in the furnace, we provide a unit type pulverizer 15 connected by a pipe 16 with a suitable burner 18 mounted on the furnace wall. The pulverizer may be of any construction which will pulverize the fuel to a sufficient degree of fineness and deliver it in a current of air to the furnace.

Secondary air is supplied to the burner 18 through a branch duct 19 leading from a main duct 20, which is shown as located in the basement below the boiler room floor. A forced draft fan 22 is arranged to discharge air into the main duct. Obviously, the main duct may be extended if desired to supply air to a plurality of furnaces, but for simplicity of illustration one furnace only is shown.

Coarse fuel, such as bituminous coal, is supplied from an overhead bunker 23 through a down-spout 24 leading to the hopper 26 of the regulatable pulverizer feeder 27. The feeder 27 delivers the coarse fuel to the pulverizer at a controlled rate, and the finely pulverized fuel passes to the furnace 10, where it meets the secondary air supplied by the fan 22. Combustion of the fuel takes place in the furnace, and the gaseous products of combustion pass through the boiler 11, thereby generating steam, and are discharged through an uptake 28 which leads to a stack (not shown).

It will now be clear that if the supply of fuel and air to the furnace is increased, the boiler will generate steam at a higher rate. Furthermore, if the demand for steam is less than the rate at which steam is being generated, the steam pressure will increase. It is ordinarily desirable to

5 maintain the steam pressure substantially uniform, and this may be accomplished by controlling the supply of fuel and air in accordance with the demand for heat. In order to obtain this result, it is preferable to utilize automatically actuated regulating apparatus, thereby eliminating the necessity for constant attention on the part of the operators in charge and at the same time increasing the accuracy of the regulation.

10 As an indication of the demand for heat, we preferably use the steam pressure, and permit a slight variation in the pressure for purposes of regulation. For example, we may provide for a pressure of 400 pounds per square inch at the lowest demand or rating, and allow this pressure to drop to 390 pounds at the highest rating, thereby establishing an operating range of 10 pounds. In order to make use of this pressure change for regulation, we provide a suitable master regulator 30, which is connected by a small pipe 31 to the steam header 14 and which is preferably of the compensating type having a hydraulic piston arranged to move in accordance with the steam pressure variations. In the example mentioned, the regulator would be adjusted to make a full stroke throughout the 10-pound operating range, taking one extreme position at 400 pounds, the other extreme position at 390 pounds, and an intermediate position corresponding to each intermediate pressure. With such a construction the regulator floats with the pressure. A slight increase in the demand is accompanied by a correspondingly slight increase in the rate of combustion, and sudden extreme fluctuations in fuel feed or air flow with the resulting inefficiency are avoided.

40 A number of devices suitable for use as the master regulator 30 are available commercially, one particularly satisfactory construction being disclosed in the patent to Paul C. Temple, No. 1,890,472, granted December 13, 1932. Such an apparatus is illustrated in Fig. 2, the steam pressure is transmitted through the pipe 31 to the lower surface of the flexible pressure responsive diaphragm 32 of the regulator. A knife edge 34 mounted on the upper surface of the diaphragm supports a horizontal lever arm or beam 35 which is pivoted on a second knife edge 36 mounted in the regulator frame. The pressure of the steam on the diaphragm is balanced by weights 38 and 39 carried by the beam 35, and this beam will assume a definite position for each steam pressure within the operating range. This, it will be understood, is due to the well known fact that the effective area of a flexible diaphragm decreases as it moves in response to a pressure increase, the result of the decreased area being to arrest the movement of the beam.

60 The movements of the beam 35 in response to steam pressure changes are utilized to control the movements of a piston 40 slidably mounted in a stationary vertical cylinder 42. A piston rod 43 joined to the piston extends upwardly through a stuffing box 44 in the upper end of the cylinder, and is connected to the regulatable feeding device 27 of the pulverizer 15 by means of a link 45, a bell crank 46 and a rod 47. These parts are so proportioned and arranged that downward movement of the piston will decrease the feed of fuel, and a complete stroke of the piston will move the fuel feeder throughout the complete range of fuel burning rates desired for the particular installation.

70 The piston 40 is actuated by fluid pressure under the control of a pilot valve 48 connected to

the beam 35. This valve is preferably of the well known balanced piston type and is mounted in a valve casing 50. The stem 51 of the valve extends upwardly through a stuffing box 52 in the casing and is connected to a horizontal lever 54 which is joined to the beam 35 by a vertical link 55. The lever 54 is supported intermediate its length on a fulcrum 56 formed on the upper end of a vertical link 57. These parts are so arranged that whenever the beam 22 is raised by an increase in steam pressure, the pilot valve will move downwardly, and vice versa.

75 The valve casing 50 is divided internally by means of partitions into four separate chambers. The central chamber 59 is supplied with fluid under pressure through a pipe 60. This operating fluid may be air, water, oil or any other suitable gas or liquid as desired. The exhaust chamber 61 extends to both ends of the casing and is connected to an exhaust pipe 63, which is intended to carry away the spent operating fluid, the disposal of which depends upon its character. If compressed air is being used, the pipe 63 may discharge to atmosphere. If water is being used, the discharge pipe will lead to a drain. If oil is being used, it is returned to a reservoir. Above the central inlet chamber 59, and between the inlet chamber and the exhaust chamber, we provide a chamber 64 which is connected by a pipe 65 to the lower end of the cylinder 42. The upper end of the cylinder is connected by a pipe 67 to a chamber 68 directly beneath the inlet chamber 59. For convenience in manufacture we preferably provide a hollow cylindrical sleeve 69 in which the valve 48 is slidable and which extends vertically through the chambers 64, 59 and 68. Ports 70 in the wall of the sleeve provide passages leading between each of these chambers and the interior of the sleeve, and the ends of the sleeve open into the exhaust chamber 61.

80 The pilot valve 48 and its associated parts are so arranged that whenever the valve is in the neutral position shown in Fig. 4, both ends of cylinder 42 are cut off from communication with the inlet chamber 59 and the exhaust chamber 61, and as a result the piston 40 is held stationary. If the valve is moved downwardly from its neutral position, chamber 68 and the upper end of the cylinder are connected to the inlet chamber 59, while at the same time chamber 64 and the lower end of the cylinder are connected to the exhaust chamber 61. This will admit fluid above the piston 40 and cause it to move downwardly. In a similar manner, if the valve 48 is moved upwardly from its neutral position, fluid will be admitted beneath the piston 40, the upper end of the cylinder will be connected to the exhaust, and the piston will move upwardly.

85 With the construction as so far described the piston will travel all the way to the end of its stroke after it has once been started. This of course is not desirable, and we therefore provide a compensating mechanism which serves to return the pilot valve to its neutral position and thus stop the piston after a predetermined movement, the extent of which bears a definite relationship to the change of pressure in the diaphragm chamber.

90 The compensating mechanism illustrated comprises a pair of relatively slidable members 72 and 73. The member 72 is shown as a cylindrical rod having its upper end pivoted to the piston rod 43 by means of a pin 74. This rod extends downwardly at a considerable angle with respect to the piston rod. The member 73 is

pivoted to the frame by means of a pin 75, and is shaped to slidably receive the rod 72. The member 73 has formed integral therewith a horizontally projecting slotted extension or arm 76, which is connected by means of a link 77 to one end of a lever 78. The effective length of the extension 76 may be varied by adjusting the lower end of the link 77 along the slot. The lever 78 is pivoted to the frame by means of a pin 79 intermediate of its length, and the end opposite the link 77 is pivoted to the lower end of link 57. In this way the compensating mechanism is arranged to coact with the connection between the weighted beam and the pilot valve.

15 It will now be clear that if the pressure in the control line 31 drops slightly, because of increased demand for steam, then the beam 35 will be lowered a distance proportional to the pressure drop, and will come to rest in its new position because 20 of the change in effective area of the diaphragm. As beam 35 moves downwardly, it will act through link 55 to rock lever 54 about pin 56 as a fulcrum, thus raising valve 48. This will admit fluid to the lower end of the cylinder 42 through pipe 25 65, causing piston 40 to move upwardly and increasing the fuel feed to take care of the increased demand. As the piston rod moves upwardly it will carry with it the slide rod 72, which will slide through the member 73 while at the same time 30 turning it about its pivot 75 in a clockwise direction because of the change in the angular position of the slide rod. This movement of the member 72 will be transmitted through link 77, lever 78, and link 57, thus rocking lever 54 about 35 the upper end of link 55 as a fulcrum, lowering pilot valve 48 to its neutral position and stopping piston 40 in a new position.

By adjusting the lower end of link 77 along the slot in arm 76 it is possible to alter the operating range of the regulator, that is, the amount of pressure change required to move the piston 40 through the full length of its stroke. An increase in the effective length of arm 76 will increase the operating range, and vice versa. Where the 45 demand for steam fluctuates greatly, an increased operating range is desirable as tending toward smoother operation.

It is necessary to control not only the rate of fuel feed to the pulverizer 15, but also the rate 50 of secondary air flow to the burner 18. For this purpose we utilize an adjustable damper 81 located in the branch duct 19 and provided with an external operating arm 82. In order that each 55 position of the damper 81 may result in a predetermined air flow in the duct 19, we preferably provide means for automatically controlling the pressure in the main duct 20 anterior to the damper and the pressure in the furnace chamber 10 posterior to the damper. In the embodiment illustrated, the pressure in the main duct 20 is transmitted through a pipe 83 to a regulator 84, which is connected by a cable 85 to a damper 86 located at the discharge of the fan 22. The regulator 84 controls the position of the damper 86 and maintains the pressure in the main duct 20 constant at a value sufficient to allow operation at the highest rating desired. The pressure in the furnace chamber 10 is transmitted through a pipe 88 to a regulator 89, which is connected by a cable 90 to a damper 91 located in the furnace uptake 28. The regulator 89 controls the discharge of the gaseous products of combustion and maintains a predetermined pressure in the furnace, preferably slightly below atmospheric pressure. These regulators 84 and 89 may be of various con-

structions, one suitable apparatus being disclosed in the prior patent to Terry No. 1,596,031.

We have discovered that if the damper 81 is arranged to be operated directly by a master regulator 30, the efficiency of combustion under a varying load is not as high as that theoretically obtainable. From inspection of the combustion flame, there appear to be periods during which the air flow is excessive, and other periods during which the air flow is deficient. We have furthermore discovered that this phenomenon is caused by a lag in the response of the pulverizer to a change in demand for fuel at the burner. For example, if the fuel feeder 27 and the damper 81 are both moved at the same time to a new 15 position corresponding to a higher steam demand, the air flow in duct 19 will increase instantly to the new value, but the fuel flow at the burner will increase much more slowly, and in some cases as much as 30 seconds will elapse before the fuel flow into the furnace will reach the value corresponding to the new feeder position. A similar lag in the change of fuel flow will occur when the feeder is adjusted to decrease the rate of feed, but in some cases the time lag under 20 these circumstances has been found to be less than when the feed is increased. We believe that this slowness in response is caused by the fact that during operation an appreciable quantity of fuel is present in the pulverizer in the 25 process of being pulverized, and that this quantity increases as the rate of pulverization increases. Hence, when the feed of coarse fuel is increased, a portion of the increased incoming coarse fuel must be used to build up the quantity 30 of fuel in the pulverizer, and the entire increased flow is not at once available at the burner. Similarly, a decrease in the fuel feed does not produce an immediate corresponding decrease in flow at the burner, since a portion of the fuel in the 35 pulverizer must first be discharged. Apparently certain types of pulverizers are able to clear themselves more quickly than they can load up, and hence will follow a decreasing demand more closely than an increasing demand. A similar 40 time lag is encountered in the so-called storage system of burning pulverized fuel, though usually to a considerably less extent.

Pulverized fuel is burned in suspension in the furnace chamber, and each particle of fuel is 45 present within the chamber for a very few seconds only. It is therefore essential that the correct amount of air to burn the fuel should enter the furnace at exactly the same time as the fuel enters. It is not enough that the average ratio 50 of fuel and air flows should be maintained correct, but it is necessary that the ratio should be correct at every instant during operation.

We have found that we can obtain the desired result by causing all changes in the rate of air 55 flow to be made more slowly than the corresponding changes in the adjustment of the fuel feeder. This is preferably accomplished by initiating a change in the position of the damper 81 substantially simultaneously with the start of each 60 change in the adjustment of the feeder 27, and moving the damper more slowly than the feeder, so that the damper will reach its final position after each change in demand at substantially the same instant as the rate of fuel flow at the burner 65 70 75 completes its change in value. In this way the desired fuel and air ratio can be maintained at all times.

The preferred form of apparatus for carrying out this method comprises a secondary regulator 75

93 controlled by the master regulator 30 and connected to the air damper 81. This secondary regulator comprises a vertical cylinder 94 within which a piston 95 is slideable. A piston rod 97 extends upwardly from the piston and through a stuffing box 98 in the upper portion of the cylinder. The piston rod is connected by a link 99, bell crank 100, and rod 101 to the arm 82 of the burner air damper 81, these parts being so proportioned and arranged that downward movement of the piston will close the damper, and a complete stroke of the piston will move the damper sufficiently to cover the entire air flow range desired.

The movements of the piston 95 are controlled by a pilot valve mounted in a valve casing 102, these parts preferably being identical with the corresponding parts of the master regulator 30. An inlet pipe 103 and an exhaust pipe 104 are connected to the valve casing 102. Pipes 105 and 106 connect the valve casing with the lower and upper ends respectively of the cylinder 94. The valve stem 107 is actuated by a horizontal lever 108 which is connected by a vertical link 109 to an arm 110 pivoted to the regulator frame and forming a control member. The lever 108 is pivoted intermediate its length to the upper end of a vertical link 112.

The arm 110 is controlled by the master regulator 30, and for this purpose we have illustrated a vertical rod 113, a lever 114, and a link 115. The master regulator is shown as provided for convenience with a piston rod 117 extending downwardly from piston 40 and through a stuffing box 118 at the lower end of cylinder 42, the lower end of the piston rod being connected to the link 115. The master regulator thus serves to move the arm 110 in a manner corresponding to the movements of the piston 40.

The secondary regulator 93 is shown as provided with a compensating mechanism identical with that of the master regulator. This comprises a rod 120 pivoted at its upper end to the piston rod 97 and slideable through a member 121 pivoted to the regulator frame. The member 121 has a horizontally extending slotted arm 122 which is connected by a vertical link 124 to one end of a horizontal lever 125. The lever 125 is pivoted intermediate its length to the regulator frame, and is connected at one end to the link 112.

It will now be seen that movements of the master regulator will move arm 110 and open the pilot valve, thus admitting fluid to the cylinder 94 and causing movement of the piston 95 and the air damper 81 actuated thereby. The compensating mechanism will return the pilot valve to its neutral position and arrest the piston in a definite predetermined position dependent upon the extent of the master regulator movement.

In order that the movements of the air damper 81 may be slower than the movements of the fuel feeder 27, whereby we may overcome the difficulties caused by the lag in pulverizer response as heretofore explained, we preferably provide means to throttle or restrict the rate of flow of fluid to or from the cylinder 94. This serves to retard the piston 95 without affecting its final position after a change in demand. Since the lag may be different in opposite directions, we preferably provide separate adjustable throttling means to control the fluid flow to each end of the cylinder. Obviously, it is immaterial whether the speed of the piston is retarded by restricting the flow into the cylinder or the flow out of the cylinder, and either arrangement will, it is believed, provide the desired operation.

The preferred construction illustrated comprises a valve 128 connecting the pipe 105 with the pilot valve casing 102, and a second valve 129 connecting the pipe 106 with the pilot valve casing. The valve 128 is shown in detail in Fig. 5, and the valve 129 may be and preferably is an exact duplicate thereof. Referring now to Fig. 5, the valve 128 comprises a hollow casing 131 forming a passage for the flow of fluid therethrough. A partition wall 132 extends across the interior of the casing, and an opening 133 is provided in this partition, the flow through the opening being controlled by an adjustable needle valve member 134 screw threaded in the casing. A stuffing box 135 prevents external leakage past the valve member. 15

It will be clear that when one of these valves is conducting fluid to one end of the cylinder, the other valve is conducting fluid away from the other end of the cylinder. In order that the adjustment of each valve may affect the piston speed 20 in one direction only, we provide a check-valve controlled by-pass around each valve. Such a by-pass is shown incorporated in the valve casing itself, and comprises a second opening 137 in the partition 132, controlled by a ball check valve 138 25 held in place by a light compression spring 139. A pipe nipple 140 serves to hold these parts in the proper relationship, as well as to connect the valve casing 131 to the pilot valve casing 102. The ball check 138 allows fluid to flow freely in a 30 direction away from the cylinder 94, but fluid flowing toward the cylinder must pass through the opening 133 controlled by the needle valve. Hence each needle valve may be adjusted to give an independent control over the speed of the 35 piston movement in opposite directions. Valve 128 controls the upward piston speed, and valve 129 controls the downward piston speed.

The operation of the invention will now be apparent from the above disclosure. Whenever 40 a change occurs in the demand for heat, the piston of the master regulator 30 will assume a new position corresponding to the new demand, and will at the same time adjust both the fuel feeder 27 and the secondary regulator control arm 45 110. The secondary regulator piston 95 will immediately begin to move and adjust the air damper 81 to change the rate of air flow. The needle valves 128 and 129 are so adjusted, preferably after installation, that they retard the movements of the piston 95, and allow the damper 81 to reach its final position of adjustment at the same instant that the change in fuel feed has become fully effective at the burner 18. If there is a difference between the rate at which the pulverizer 15 will clear itself and the rate at which it will pick up a load, the valves 128 and 129 can be readily adjusted to take care of these conditions. It is merely necessary to throttle one valve more than the other. The adjustment of 50 the piston speed in one direction has no effect on the speed in the other direction, since the check valves 138 allow free discharge of the fluid from that end of the cylinder 94 toward which the regulator piston 95 is moving. 55

Our invention makes it possible to obtain a desired predetermined ratio between the rates of flow of the fuel and air into the furnace at all ratings and particularly during periods of change in the demand for heat. Difficulties caused by 60 variations in the performance characteristics of different pulverizers are overcome, and if a change in the character of the fuel alters the time lag in the pulverizer, it is a simple matter to readjust the secondary regulator to meet the new 70 75

conditions. The apparatus disclosed is of simple and inexpensive construction, and will result in a marked increase in combustion efficiency and a consequent saving in fuel.

5 Having thus described our invention, what we claim as new and desire to secure by Letters Patent is:

1. The method of controlling a pulverized fuel burning system comprising the steps of varying 10 the feed of fuel in accordance with the demand for heat, initiating a change in air flow substantially simultaneously with the start of each change in fuel feed, and making all air flow changes more slowly than the corresponding 15 changes in fuel feed.

2. The method of controlling a pulverized fuel burning system having a fuel feeder and an air damper, comprising the steps of adjusting the fuel feeder in accordance with the demand for 20 heat, initiating an adjustment of the air damper substantially simultaneously with the start of each fuel feeder adjustment, and making all air damper adjustments more slowly than the corresponding fuel feeder adjustments.

25 3. The method of controlling a direct fired pulverized fuel burning system comprising the steps of controlling the feed of coarse fuel to the pulverizer in accordance with the demand for heat, initiating an adjustment of the air flow to the furnace substantially simultaneously with the start of each change in fuel feed, and making all air flow changes more slowly than the corresponding changes in fuel feed.

4. The method of controlling a direct fired 35 pulverized fuel burning steam generating system comprising the steps of controlling the feed of coarse fuel to the pulverizer in accordance with the demand for steam, initiating an adjustment of the air flow to the furnace substantially simultaneously with the start of each change in fuel feed, and making all air flow changes more slowly than the corresponding changes in fuel feed.

5. The method of controlling a direct fired 45 pulverized fuel burning system comprising the steps of controlling the feed of coarse fuel to the pulverizer in accordance with the demand for heat, initiating an adjustment of the air flow to the furnace substantially simultaneously with the start of each change in fuel feed, and making all air flow changes so slowly in comparison with the corresponding fuel feed changes that the air flow reaches its final changed value as substantially the same instant as the change in fuel feed becomes fully effective at the furnace.

55 6. The method of controlling a direct fired pulverized fuel burning system having a forced draft damper comprising the steps of controlling the feed of coarse fuel to the pulverizer in accordance with the demand for heat, initiating an adjustment of the damper substantially simultaneously with the start of each change in fuel feed, making all damper adjustments more slowly than the corresponding changes in fuel feed, maintaining a constant air pressure anterior to the damper, and controlling the discharge of the gaseous products of combustion from the furnace in accordance with the pressure in the furnace.

7. A pulverized fuel burning system comprising 70 a furnace, means to deliver a stream of primary air to the furnace, controllable means to feed pulverized fuel at a definite rate to the primary air stream, a duct for supplying secondary air to the furnace to effect complete combustion of the fuel, means to adjust the fuel feed in accordance with the demand for heat, means to

initiate an adjustment of the air supply substantially simultaneously with the start of each change in fuel feed, and means to cause all air supply adjustments to be made at a slower rate than the corresponding fuel feed adjustments.

8. A pulverized fuel burning system comprising a furnace, a pulverizer arranged to deliver pulverized fuel and primary air directly thereto, controllable means to feed coarse fuel to the pulverizer at a definite rate, a duct to supply secondary air to the furnace to effect complete combustion of the fuel, means to adjust the fuel feed in accordance with the demand for heat, means to initiate an adjustment of the air supply substantially simultaneously with each change in fuel feed, and means to cause all air supply adjustments to be made at a slower rate than the corresponding fuel feed adjustments.

9. A pulverized fuel burning system comprising a furnace, a pulverizer arranged to deliver pulverized fuel and primary air directly thereto, controllable means to feed coarse fuel to the pulverizer at a definite rate, a duct to supply secondary air to the furnace to effect complete combustion of the fuel, a master regulator arranged to control the fuel feed in accordance with the demand for heat, and a reversible secondary regulator arranged to control the secondary air supply, the secondary regulator being controlled by the master regulator and arranged to start substantially simultaneously therewith following a change in demand, the secondary regulator being arranged to operate at a slower speed than the master regulator in each direction.

10. A pulverized fuel burning system comprising a furnace, means to deliver a current of primary air to the furnace, controllable means to feed pulverized fuel at a definite rate to the primary air current, a duct for supplying secondary air to the furnace to effect complete combustion of the fuel, a master regulator arranged to control the fuel feed in accordance with the demand for heat, and a secondary regulator arranged to control the secondary air supply, the secondary regulator being controlled by the master regulator but arranged to operate at a slower speed than the master regulator.

11. A pulverized fuel burning system comprising a furnace, a pulverizer arranged to deliver pulverized fuel directly thereto, controllable means to feed coarse fuel to the pulverizer at a definite rate, a duct to supply air to the furnace, means to control both the feed of coarse fuel to the pulverizer and the air flow to the furnace in accordance with the demand for heat, means to cause each change in air flow to be made more slowly than the corresponding change in fuel feed, and means to adjust the speed of response of the air flow to an increased demand independently of the speed of response of the air flow to a decreased demand.

12. A pulverized fuel burning system comprising a furnace, a pulverizer arranged to deliver pulverized fuel directly thereto, controllable means to feed coarse fuel to the pulverizer at a definite rate, a duct to supply air to the furnace, a piston operated by fluid under pressure and connected to control the feed of the coarse fuel, a second piston operated by fluid under pressure and arranged to control the rate of air flow in the duct, means to move both of said pistons in accordance with the demand for heat, means to cause the second piston to make all air flow changes more slowly than the first piston makes the corresponding changes in fuel feed, and

means to control the speed of the second piston independently in each direction.

13. A pulverized fuel burning system comprising a furnace, a pulverizer arranged to deliver pulverized fuel directly thereto, controllable means to feed coarse fuel to the pulverizer at a definite rate, a duct to supply air to the furnace, a master regulator arranged to control the fuel feed in accordance with the demand for heat, a reversible secondary regulator arranged to control the air flow in the duct, the secondary regulator being controlled by the master regulator and arranged to operate at a slower speed than the master regulator in each direction, and means to adjust the operating speed of the secondary regulator independently in each direction.

14. Combustion control apparatus for a direct fired pulverized fuel burning system having a pulverizer and a feeding device to supply coarse fuel to the pulverizer comprising a master regulator of the compensating type arranged to control the feeding device in accordance with the demand for heat, and a reversible secondary regulator actuated by the master regulator and arranged to control the air supply to the furnace, the secondary regulator being arranged to operate at a slower speed than the master regulator in each direction.

15. Combustion control apparatus for a direct fired pulverized fuel burning system having a pulverizer and a feeding device to supply coarse fuel to the pulverizer comprising a master regulator of the compensating type arranged to con-

trol the feeding device in accordance with the demand for heat, a cylinder, a double acting hydraulic piston slidable therein and connected to control the air supply to the furnace, a pilot valve, means connecting the master regulator with the pilot valve, compensating mechanism connecting the piston with the pilot valve, means providing two passages for fluid leading from the pilot valve to opposite ends of the cylinder, a manually adjustable valve in each passage, means providing a by-pass around each manually adjustable valve, and a check valve in each by-pass, whereby the piston speed in one direction may be regulated without affecting its speed in the opposite direction.

16. Combustion control apparatus for a direct fired pulverized fuel burning system having a pulverizer and a feeding device to supply coarse fuel to the pulverizer comprising a master regulator of the compensating type arranged to control the feeding device in accordance with the demand for heat, a secondary regulator of the compensating type actuated by the master regulator and arranged to control the air supply to the furnace, the secondary regulator being arranged to make all changes in air supply more slowly than the corresponding changes in fuel supply, and means to adjust the operating speed of the secondary regulator independently in each direction.
